CLAIM

The ornamental design for a weight bearing device, as shown and described.

DESCRIPTION

FIG. 1 is a top perspective view of a weight bearing device of the present invention;

FIG. 2 is a bottom perspective view of the weight bearing device of FIG. 1;

FIG. 3 is a right side view of the weight bearing device of FIG. 1;

FIG. 4 is a left side view of the weight bearing device of FIG. 1;

FIG. 5 is a front view of the weight bearing device of FIG. 1;

FIG. 6 is a rear view of the weight bearing device of FIG. 1;

FIG. 7 is a top view of the weight bearing device of FIG. 1; and,

FIG. 8 is a bottom view of the weight bearing device of FIG. 1.

The broken line showing of environmental structure is included for the purpose of illustrating subject matter that forms no part of the claimed design.

1 Claim, 8 Drawing Sheets
